William B. Benert, St. Paul, Minn., assignor to Electro-Med, Inc., Minneapolis, Minn., a corporation of Minnesota

Filed Sept. 20, 1961, Ser. No. 66,767

Term of patent 3½ years

(Cl. D52—3)

FIG. 4

FIG. 3

FIG. 1 is a front perspective view of a cigarette vending machine, showing my new design;

FIG. 2 is a rear perspective view thereof;

FIG. 3 is a view thereof in side elevation; and

FIG. 4 is a top plan view thereof.

The pattern seen behind the display window in FIG. 1 is understood to be repeated throughout the area shown, and represents a perforated screen.

The broken line packages in the display window are shown for illustrative purposes only.

I claim:

The ornamental design for a cigarette vending machine, as shown and described.
